(57) **CLAIM**

I claim, the ornamental design for a splash resistant beverage lid, as shown and described.

DESCRIPTION

FIG. 1 is a perspective view of my unassembled new splash resistant beverage lid design

FIG. 2 is a top view of my unassembled new splash resistant beverage lid design

FIG. 3 is the bottom view of my unassembled new splash resistant beverage lid design

FIG. 4 is a left side view of my unassembled new splash resistant beverage lid design

FIG. 5 is a right side view of my unassembled new splash resistant beverage lid design

FIG. 6 is a front elevation of my unassembled new splash resistant beverage lid design

FIG. 7 is a rear elevation of my unassembled new splash resistant beverage lid design; and,

FIG. 8 is a perspective view of my assembled new splash resistant beverage lid design.

1 Claim, 6 Drawing Sheets
